SPRING-COILING MACHINE.

1,045,900.

Specification of Letters Patent.

Patented Dec. 3, 1912.

Application filed May 24, 1909. Serial No. 497,916.

To all whom it may concern:

Be it known that I, FRANK H. SLEEPER, a citizen of the Dominion of Canada, residing at Worcester, in the county of Worcester and 5 Commonwealth of Massachusetts, have invented a new and useful Improvement in Spring-Coiling Machines, of which the following is a specification, accompanied by drawings forming a part of the same, in 10 which—

Figure 1 represents a plan view of a spring coiling machine embodying my present invention. Fig. 2 is a side view. Fig. 3 is an end view. Fig. 4 is a detached view showing the cutting mechanism in plan view. Fig. 5 is a detached front view of the cutting mechanism. Fig. 6 is a central vertical sectional view of the hollow spindle carrying the coiling arbor. Fig. 7 is a side view 20 of the gear 15 and clutch by which it is connected with the shaft 12. Fig. 8 is a detached front view of the feed rolls. Figs. 9 and 10 are diagrammatic views showing different positions of the coiling spindle in the 25 operation of coiling a spring, and Figs. 11, 12 and 13 illustrate different forms of springs which may be produced by different adjustments of the machine.

Similar reference letters and figures refer 30 to similar parts in the different views.

My present invention relates to a machine for coiling wire springs, having one or both ends of the wire of which the spring is formed projecting at a desired angle and 35 length from the coils, such springs being known in the trade as jig springs, three forms of such springs being illustrated in Figs. 11, 12 and 13 of the accompanying drawings.

40 My invention has for its object to provide an automatic machine for the production of jig springs from a continuous coil of wire, and capable of certain novel adjustments by which the form of the springs can be varied, 45 and it consists in the construction and arrangement of parts as hereinafter described and pointed out in the annexed claims.

Referring to the accompanying drawings, 1 denotes a supporting stand upon which 50 the operative parts of the machine are mounted. Power is applied to the machine through a belt pulley 2 carried upon one end of a driving shaft 3. Upon the opposite end of the shaft 3 is a pinion 4 which engages a

gear 5, having on one side diametrical ways 55 6, 6, for an adjustable head 7 carrying a crank pin 8 connected by a rod 9 with a rack 10, sliding on horizontal ways on the stand 1 and engaging a pinion 11 on the lower end of the vertical shaft 12. The upper end of the shaft 12 is provided with a clutch, one member 13 of the clutch having a single tooth engaging a corresponding tooth on the other clutch member 14 formed on the side of a gear 15, capable of turning 65 loosely on the shaft 12 and engaging a pinion 16 on a hollow vertical spindle 17, journaled in bearings 18 and 19 and provided at its upper end with an external screw threaded collar 20, the threads of which are engaged by a fixed beveled stud 21 held in the framework of the machine. As the spindle 17 and screw threaded collar 20 are rotated, the engagement of the screw threaded collar with the stud 21 will cause a rising or 70 falling movement of the spindle 17 according to the direction of rotation of the spindle. The lower end of the spindle 17 receives an arbor 22 provided with a collar 23 which is preferably integral with the arbor 80 and carries a stud 24, which is held parallel with the axis of the arbor 22 and at a sufficient radial distance therefrom to allow the insertion of the wire to be coiled between the arbor 22 and stud 24 thereby holding the 85 first coil of the wire upon the arbor. Adjustably attached to the bearing 19 is a stop 25 projecting into the path of a radially projecting stud 25^a held in the hollow spindle 17 in order to check the rotation of the spindle, 90 and thereby limit its downward movement.

Adjustable on horizontal ways 26 on the stand 1 is a plate 27, and adjustable on the plate 27 in ways 28 at right angles to the ways 26 is a plate 29, which carries a hollow 95 steel bushing 30 through which the wire 31 to be coiled passes to the coiling arbor 22. Sliding upon the front side of the plate 27 is a plate 32, provided with a cam roll 33 which is held in contact with a cam 34 carried upon a shaft 35 by means of a spring 34^a, having one end attached to the plate 32 and the opposite end to a fixed stud. Adjustably held in the sliding plate 32 is a cutting bar 36, capable of being longitudinally 100 adjusted in the plate 32 by means of a screw 37. Attached to the plate 27 by screws 38 is a plate 39 provided with a bearing 40 for

the shaft 35. The shaft 35 is connected by miter gears 41 with a shaft 42, which carries upon its end the gear 5 and, as the shaft 35 and cam 34 rotate, the cam projection 43, during each revolution of the cam, contacts with the cam roll 33 to slide the plate 32 carrying the cutting bar 36 held therein past the hole in the bushing 30, thereby severing the wire between the bushing 30 and the rotating arbor 22.

10 The wire 31 to be coiled is taken from a reel in a continuous length between the straightening rolls 44 of the usual construction, and between feed rolls 45 and 46 carried on vertical spindles which are connected by gears 47 and 48. One of the spindles of the feed rolls is provided with a pinion 49, which engages a gear 50 carrying a pinion 51 which is engaged by a ratchet 20 52 attached to a vertical spindle 53, carrying a pinion 54 engaged by a sliding rack 55. The rack 55 is provided with a cam roll 56, and the rack 55 is actuated in one direction by a cam 57 and in the opposite direction by a spring 58, attached at one end to the rack and at the opposite end to a fixed portion of the framework. Adjustably clamped to the rack 55 is a stop plate 59, which contacts with a fixed bearing 60 for the rack 55 as the latter is retracted by the tension of the spring 58. The adjustment of the stop plate 59 determines the reverse movement of the rack as actuated by the spring 58 and, consequently, the forward movement of the rack as actuated by the cam 57.

At the beginning of the coiling operation, the hollow spindle 17 is in its lowest position, with the arbor 22 and stud 24 in position to receive the wire to be coiled between the arbor and stud and immediately beneath the collar 23. This position of the coiling arbor 22 and stud 24 is determined by the contact of the stud 25 against the stop 25, the latter being adjustable on the bearing 19 for this purpose. The diameter of the arbor 22 determines the diameter of the coiled spring, and the number of upward rotations of the arbor during forward movement of the wire determines the number of coils in the spring. The pitch of the screw threaded collar 20 determines the distance separating each coil, enabling the wire to be coiled closely together or more or less open, and also enabling the vertical feeding movement of the coiling arbor to be adjusted for wire of different sizes. The coiling arbor and the screw threaded collar are, therefore, made removable and are held in place by a clamping bolt 61, having a polygonal head 62 at its upper end bearing against a washer 63 which rests upon the top of the screw threaded collar 20, holding the latter firmly against the shoulder 64 formed on the spindle 17.

The lower end of the clamping bolt 61 is screw threaded and inserted in a screw threaded hole in the upper end of the coiling arbor 22, which is preferably slightly tapered and drawn into a tapered hole in the lower end of the spindle 17. The pinion 16, which is preferably integral with the spindle 17, is elongated to provide for the vertical movement of the spindle 17, and passes into the bearing 18 as the spindle 75 moves downwardly.

In Figs. 11, 12 and 13 I have shown three forms of jig springs among a great variety capable of being automatically coiled upon the machine herein described. The three 80 forms illustrated in Figs. 11, 12 and 13 differ principally in the position and length of the arms which are formed by the projecting ends of the wire at opposite ends of the spring, spring 65 showing two arms 66 and 67 of equal length and standing at right angles to each other. 68 denotes a spring having two arms 69 and 70 of unequal lengths and placed parallel to each other, but extending in opposite directions, and 71 90 denotes a spring having two arms 72 and 73 of unequal lengths, but projecting in the same direction.

In the operation of coiling a spring, such as that shown at 65, Fig. 11, the wire to be 95 coiled is projected through the bushing 30 between the coiling arbor 22 and the stud 24 a sufficient distance to form the arm 67, the rotation of the coiling arbor then winds the spring the desired number of coils during the upward movement of the coiling arbor. The first coil of the spring is held upon the arbor between the stud 24 and the arbor and, as the arbor gradually moves upward, the wire is wound upon it in coils, 100 with the distance between the coils governed by the pitch of the screw threaded collar 20. The upward movement of the arbor is continued until a spring of the desired length is formed upon the arbor below the plate 105 23. The reverse or return movement of the arbor is then begun by reversing the movement of the rack bar 10 and as soon as the slight recoil in the wound spring has taken place, due to the elasticity of the wire, 110 the cutting bar 36 is pushed forward by the contact of the cam projection 43 with the cam roll 33 cutting off the wire to form the arm 66. The reverse movement of the arbor is then continued to bring the arbor 115 and stud 24 into the position from which they started, arranged to receive the wire to be coiled between them, when the operation of forming a spring may be repeated. The elasticity of the wound spring, causing 120 the slight recoil referred to above, separates the spring from the arbor and allows it to drop off as soon as the wire is cut. The number and position of the coils of the spring 65 determine the relative position of 130

the arms 66 and 67. The length of the arm 66 is determined by adjusting the plate 27 on the horizontal ways 26, in order to bring the cutting mechanism the desired distance 5 from the coiling arbor.

During the operation of coiling, the coiling arbor is driven by the positive engagement of the clutch mechanism between the shaft 12 and gear 15. During the reverse 10 movement of the shaft 12, the clutch teeth are held in contact by the spring 14^a which connects the clutch member 13 and the gear 15. The clutch tooth on the gear 15 follows the clutch tooth on the clutch member 13 until the stud 25^a strikes the stop plate 25, which checks the reverse movement of the spindle 17 and gear 15, and any further movement of the shaft 12 would, of course, cause the teeth of the clutch mechanism to 20 separate and the spring 14^a to yield. The cutting bar 36 is longitudinally adjusted in the plate 32 by means of a screw 37. The adjustment of the plate 29 on the horizontal ways 28 of the plate 27 enables the 25 bushing 30 and cutting bar 36 to be laterally adjusted, so as to feed the wire between the coiling arbor 22 and stud 24. By changing the screw threaded collar and reversing the operation of the coiling mechanism, a left 30 hand spring can be coiled.

I claim,

1. In a machine for coiling wire springs, a rotatable arbor, means for holding the end of a wire from rotation on said arbor, 35 means for moving said arbor longitudinally by the rotation of said arbor, feed rolls for feeding said wire to said arbor, and adjustable automatic means for imparting rotation to said rolls during the rotation of said 40 arbor.

2. In a machine for coiling wire springs, a rotatable arbor, means for moving said arbor longitudinally, means for feeding a wire to said arbor, means between said feeding 45 mechanism and said arbor for determining the line of feed of said wire, and means between said mechanism for determining the line of feed and said arbor for severing said wire.

3. In a machine for coiling wire springs, a longitudinally moving arbor, means for rotating said arbor, means for feeding a wire to said arbor, adjustable means for determining the line of feed of said wire, and 55 means next said arbor for severing said wire in said line of feed, said severing means adjustable relatively to said mechanism for determining the line of feed.

4. In a machine for coiling wire springs, 60 a rotatable arbor, means for moving said arbor longitudinally by the rotation of said arbor, means for feeding a wire to said arbor in a predetermined line of feed, means between said arbor and said feeding mechanism for severing said wire, and means for 65

adjusting said severing mechanism relatively to said line of feed and also relatively to said arbor.

5. In a machine for coiling wire springs, a rotatable arbor, means for moving said 70 arbor longitudinally by the rotation of said arbor, means for feeding a wire to said arbor, said means arranged to operate relatively to the rotation of said arbor, means between said feeding mechanism and said 75 arbor for severing said wire, and means for varying the distance between said severing mechanism and said arbor.

6. In a machine for coiling wire springs, a rotatable arbor, means for moving said 80 arbor longitudinally by the rotation of said arbor, means for feeding a wire to said arbor, arranged to operate relatively to the rotation of said arbor, and means between said feeding mechanism and said arbor for severing 85 the wire, said severing means arranged to operate relatively to said feeding mechanism.

7. In a machine for coiling wire springs, a rotatable arbor, means for moving said 90 arbor longitudinally by the rotation of said arbor, means for feeding a wire to said arbor relatively to its rotation in one direction, with the direction of rotation of said arbor arranged to be reversed as desired, 95 thereby reversing the lengthwise movement of said arbor, and adjustable means for automatically checking the reverse rotation of said arbor at a predetermined point.

8. In a machine for coiling wire springs, 100 a vertical arbor having its lower end free for the delivery of a coiled spring by gravity, means for rotating said arbor, means for feeding a wire to said arbor, adjustably arranged to operate relatively to the rotation 105 of said arbor, and means for imparting an upward movement to said arbor during the rotation of said arbor.

9. In a machine for coiling wire springs, a vertical arbor, means for rotating said arbor, means for imparting an upward movement to said arbor during its rotation, means for feeding a wire to said arbor relatively to its rotation, means between said feeding mechanism and said arbor for severing 110 said wire, means for reversing the rotation of said arbor to impart a downward movement thereto, and means for adjustably determining the position of the arbor to end its downward movement. 120

10. In a machine for coiling wire springs, the combination of a longitudinally moving arbor, means for rotating said arbor, a feeding mechanism operating relatively to the rotation of said arbor, a bushing between 125 said feeding mechanism and said arbor for determining the line of feed to said arbor, and a severing mechanism between said bushing and said arbor.

11. In an automatic machine for coiling 130

wire springs, a rotatable arbor, means for rotating said arbor, means for moving said arbor longitudinally by the rotation of said arbor, feed rolls for feeding a wire to said arbor, means for rotating said feed rolls relatively to the rotation of said arbor, a bushing between said feed rolls and said arbor to receive said wire as it is fed to said arbor, and a cutting mechanism for severing 10 said wire between said bushing and said arbor.

12. In an automatic machine for coiling wire springs, a rotatable arbor, means for moving said arbor longitudinally by the rotation of said arbor, means for feeding a wire to said arbor arranged to operate relatively to the rotation of said arbor, a bushing between said feeding mechanism and said arbor, said bushing adjustable relatively to the feed line of the wire and also 20 to said arbor, a cutting mechanism between

said bushing and said arbor, said cutting mechanism adjustable relatively to the feed line of the wire and, with said bushing, relatively to said arbor, and means for operating 25 said cutting mechanism relatively to said feeding mechanism.

13. In an automatic machine for coiling wire springs, a rotatable arbor, means for moving said arbor longitudinally, means for 30 feeding a predetermined length of wire to said arbor, an adjustable bushing between said feeding mechanism and said arbor, and a cutting mechanism between said bushing and said arbor. 35

Dated this twenty-second day of May 1909.

FRANK H. SLEEPER.
